UNITED STATES PATENT OFFICE.

ARTHUR R. SIEGLER, OF DENVER, COLORADO.

FLUID-TURBINE ROTOR.

Application filed April 13, 1925. Serial No. 22,789.

This invention relates to turbines designed to abstract power from a current of fluid.

To improve the efficiency of turbines of this class is the principal object of this invention.

Another object is to provide passages in the turbine rotor so designed that the resultant motion between the current of fluid and the rotation of the rotor will act to gradually reverse the direction of flow of the current so as to discharge it in a direction opposite from that in which it enters the rotor.

A further object is to so arrange the rotor passages as to obtain a maximum number of passages in a minimum of space.

A still further object is to combine in one rotor two complete similar sets of passages.

Other objects and advantages reside in the detail construction of the invention, which results in simplicity, economy, and efficiency, and which will become more apparent from the following description.

In the following detailed description of the invention, reference is had to the accompanying drawing which forms a part hereof. Like numerals refer to like parts in all views of the drawing and throughout the description.

30 In the drawing:

Fig. 1 is a skeleton side elevation of my improved rotor for fluid turbines.

Fig. 2 is a partial peripheral development of Fig. 1. In this view the periphery of the rotor has been straightened, for purposes of illustration, so that the intake openings of the passages lie in the same plane.

In Figs. 1 and 2, the passages of the rotor are shown in outline as though they were formed of sheet metal and were independent of each other. In actual practice, however, the passages would be cast integrally in a circular block or rotor 27 as illustrated in the remaining views.

Fig. 3 is a side elevation of the improved rotor illustrated in Fig. 1, the passages being cast or formed within a circular block.

Fig. 4 is an edge elevation of the rotor illustrated in Fig. 3.

Fig. 5 is an edge elevation of an alternate form of the rotor to be later described.

Fig. 6 is a diagrammatic view illustrating the direction of flow of the driving current.

Fig. 7 is a detail skeleton view illustrating the arrangement of the passages when brought into close proximity.

The object of the specific curvature of the passages is to cause the current illustrated at 10, to travel in a substantially straight line within the rotor, diagrammed at 11 in Fig. 6, to a desired point, such as at 12. From this point the current is turned in a gradual arc to a discharge, at 13, at the axis, where it will emerge in a direction substantially opposite from that in which it entered the rotor.

To accomplish this, I employ a series of similarly contoured passages 14. Each of these passages enters the rotor at 22 in a radial direction immediately curving outward in the direction of rotation toward the periphery of the wheel, as illustrated at 15, to a junction point 16 where a comparatively sharp turn is made. From the junction point 16, the passage curves simultaneously toward the axis and toward the face of the rotor, as shown at 17 to a discharge opening 18 adjacent the axis of the rotor. The curve of the passage as it passes toward the axis constantly approaches a radial line.

In cross section, the passages 14 are rectangular and oblong in shape. At the periphery, the greatest width of the passage extends at right angles to the axis of the rotor. From this point to the discharge, the passage is turned or twisted, its greatest width swinging first toward a parallel to the axis thence to a substantially radial position at the discharge of the rotor.

Assuming the current to be entering the rotor at the point indicated by the arrow 19, in Fig. 1, it will be seen that the current will flow in a straight line to the junction point 16. The intake or mouth of a given passage rises as the wheel rotates but, since the fluid is moving away from the intake and the passage is curved inward, this rotation will result in but slightly distorting the line of flow of the fluid and a given point in the fluid will move in a substantially straight line to the point 12, as diagrammed in Fig. 6. This slight distortion abstracts power from the current flow across the top of the wheel. The cross sectional twist in the passages also results in friction to the flow of current and abstracts power therefrom.

In the normal operation, the current entering at 19 will reach the sharp junction in the passages 16 at a point in the travel indicated by the star 20. At this point, the current is turned from its substantially straight line flow and reversed, as to direction of

flow, in the spirally curved passage 17. In flowing down the curved passage 17, it will exert a driving force on the outer wall of the passage toward the direction of rotation until it discharges at 18. The friction to the flow in the passage 15, the sharp turn at 16, and the force exerted against the outer wall of the passage at 17, will all co-act to abstract the power from the current and rectify it into circular motion of the rotor.

In order to increase the number of passages in a rotor, I prefer to arrange them in staggered relation, as illustrated in Figs. 1 and 2, that is, each alternate passage will discharge at one face of the rotor 27 while the remaining alternate passages will discharge at the opposite face of the rotor. This arrangement allows the adjacent passages to immediately overlap each other, as well as overlap the alternate passages, so that there will be at various radii of the rotor, such as indicated by the line 21—21 Fig. 2, three overlapping passages. This arrangement results in a very compact rotor equalling in power the usual type rotors of much greater diameters.

In Fig. 5, I have illustrated an alternate form of the rotor in which two independent series of passages 23 and 24 are carried in the rotor. The entire series 23 discharge at the side 25 of the rotor while the entire series 24 discharge at the side 26 of the rotor. With this arrangement, I obtain practically double the power delivery of a rotor of the same dimensions having a single series of passages.

The passages in the rotor have been illustrated slightly spaced apart. They can, however, be brought into close proximity with but a thin vane between the intake openings 22 as illustrated in Fig. 7. When placed thus, it is necessary to bevel off the corners, as illustrated in this view, so as to allow the alternate passages to be bent away from each other. This beveling of the corners results in the intake openings of rhomboidal shape. This specific shape of intake opening has been found to have a great advantage over the usual rectangular shape in that it allows a passage to gradually open to and close from the intake opening of the turbine and allows the openings to overlap each other so that the pulsation or interruption of the flow is reduced to a minimum.

While a specific form of the invention has been described and illustrated herein, it is desired to be understood that the same may be varied, within the scope of the appended claims, without departing from the spirit of the invention.

Having thus described the invention, what I claim and desire secured by Letters Patent is:—

1. In a turbine rotor, a series of passages,

said passages entering said rotor at the periphery in a radial direction, curving outward toward the periphery thereof and toward the direction of travel thence curving inward towards a radial line to a discharge 70 adjacent the axis thereof.

2. In a turbine rotor, a series of passages, said passages entering said rotor at the periphery in a radial direction, curving outward toward the periphery thereof and toward the direction of travel thence curving inward towards a radial line to a discharge 75 adjacent the axis thereof, said curving outward and said curving inward portions intersecting at angle.

3. In a turbine rotor, the combination of a series of passages entering at the periphery of said rotor and curving, in the direction of travel, outward toward said periphery thence curving inward in the direction of travel and discharging adjacent the axis at one face of the rotor, and a second series of similar passages 85 of similar passages alternating with the passages of said first series and discharging from the opposite face of said rotor.

4. In a turbine rotor, a series of passages entering at the periphery of said rotor and curving, in the direction of travel, outward toward said periphery thence curving inward in the direction of travel and discharging adjacent the axis at one face of the rotor, and a second series of similar passages 90 alternating with the passages of said first series and discharging from the opposite face of said rotor, the passages of said second series overlapping the passages of said first series in said rotor.

5. In a turbine rotor, a series of passages entering at the periphery of said rotor and curving, in the direction of travel, outward toward said periphery thence curving inward in the direction of travel and discharging adjacent the axis at one face of the rotor, and a second series of similar passages alternating with the passages of said first series and discharging from the opposite face of said 105 rotor, the passages in each series overlapping the passages in the other series and passages in the same series.

6. In a turbine rotor, the combination of a series of passages entering at the periphery of said rotor and curving outward toward the periphery in the direction of travel of the rotor thence curving inward in the direction of travel and discharging adjacent 115 the axis at one face of the rotor and a second series of similar passages alternating with the passages of said first series and discharging from the opposite face of said rotor, the cross sections of the passages toward 120 their intaking ends being rhomboidal in shape.

In testimony whereof, I affix my signature.

ARTHUR R. SIEGLER.
